GUY WIRE GUARD

Jasper Blackburn, Webster Groves, and Henry W. Heller, St. Louis, Mo.; said Heller assignor to said Blackburn

Application July 25, 1930. Serial No. 470,650

15 Claims. (Cl. 189—31.5)

Our invention relates to improvements in guy wire guards, and has for its primary object a guy wire guard formed of two sections which can be readily attached around an existing guy wire.

A further object is to construct a guy wire guard which can be clamped on to the guy wire in such a manner that longitudinal movement of the guard is impossible.

10 A still further object is to construct a guy wire guard in which the securing means must be operated by a specially shaped tool so that unauthorized persons cannot tamper with the fastening means and remove the guard.

15 In the drawing, Fig. 1 is a side elevation of our guard showing the same attached to a guy wire.

Fig. 2 is an enlarged cross section taken on the line 2—2 of Fig. 1 with the guy wire removed.

20 Fig. 3 is a fragmental plan view of the upper section of the guard showing the clamping member.

Fig. 4 is a fragmental view of the lower section of the guard showing the wire receiving member.

Fig. 5 is a fragmental vertical longitudinal section of our guard showing the guy wire in clamped position.

30 Fig. 6 is a cross section of a modified form of guard and

Fig. 7 is a top plan view of one of the securing screws made use of.

In the construction of our device, we employ 35 a guard having a lower member 8 and an upper member 9. These members are formed of sheet metal and are substantially semicircular in cross section. One end of each of these members is preferably rolled in as indicated by the number 10 so as to leave a rounded upper end.

Placed in the member 8 is a block 11 which block is provided with a central groove 12. This groove may be provided with spiral grooves 13 so that when a stranded guy wire is used, the 45 strands will fit into these grooves and assist in holding the guard in place. The block 11 may be provided with perforated ears 14 through which rivets 16 pass. These rivets also pass through the member 8 and are for the purpose 50 of securing the block in position.

The block 11 is also provided with outwardly extending ribs 17 which rest on the edges of the member 8 and assist in centering the block so that the groove 12 will always be in the 55 same position; in other words, when a series of

blocks as illustrated in Fig. 1 are placed in the member 8, all of the grooves 12 will be in alignment. It will be noted that the block 11, extends upward some distance beyond the upper edges of the member 8 and this projecting portion is provided with openings or recesses 18, the purpose of which will be explained in detail later.

The member 9 has secured therein a block 19. This block is provided with outwardly extending 65 ribs 20 which serve the same purpose as the ribs 17. The block 19 is provided with a pair of extending projections 23 and with a portion 24. The portion 24 is adapted to pass over the upper surface of the block 11 while the projections 70 23 abut one edge of the block 11. This is clearly illustrated in Fig. 5. The projections 23 are provided with pins or other extensions 25 which pass into the recesses 18 and thus prevent lateral separation of the members 8 and 9. 75

The block 19 is also provided on its two end faces with recesses 26 in which the inturned ends 27 of a floating lock member 28 extend. The block 19, as well as the member 9 are provided with a screw threaded bore 29 in which a 80 set or securing screw 30 extends. This screw is provided with a polygonal recess 31 for the reception of a special tool to tighten down the screw. The block 19 may also be provided with perforated ears 32 by means of which the block 85 can be riveted in position.

In Fig. 6 we have shown a modified form of construction in which a member 33 semi-circular in cross section is employed. This member has a block 34 secured in position similar to the 90 block 19. The block 34 is provided with a pair of ears or projections 35 which are provided with a bore so as to receive a cotter key or pin 36. The block 34 is provided with a floating lock 37 which is similar to the lock 28 and with a 95 screw 38 which is similar to the screw 30. It will be noted from Fig. 6 that when the securing screw 38 is tightened, the cable 39 will have a tendency to bend the cotter key 36 downwardly and thus effectually prevent its removal by ordinary means.

We may also if found desirable form openings 40 in the member 8. These openings are for the purpose of permitting moisture which might enter the guard to pass therefrom instead of being 105 stopped and retained in this lower member by the blocks 11. The manner of attaching our device is as follows:—

The lower member 8 is placed in position on the underside of the wire, then the upper mem- 110

ber 9 is placed in position on the upper side of the wire in such a manner that the upper end of the member 9 will be above the upper end of the member 8. When the two members are in this position, the blocks 11 and 19 will be spaced apart longitudinally. The member 9 is then moved longitudinally so that the extensions 25 will enter the recesses 18. This movement is continued until the projections 23 come in contact with one face of the blocks 11. This brings the blocks of the two sections into the position illustrated in Figs. 1 and 5. After this, the fastening tool is introduced into the polygonal recess 31 formed in the screw 30 and then when the screw is turned downward, the floating lock 28 is forced against the guy wire 39 so that the same will be bound tightly between this lock and the lower portion of the groove 12 formed in the block 11 thus frictionally holding the guard in place.

It will be noted from Fig. 5 that the upper end of the screw 30 is sunk a considerable distance below the surface of the member 9, thus leaving what may be termed a pit. This pit may be filled with any suitable substance so as to prevent the lodgement or retention of moisture in the pit and at the same time, such filling material will prevent anyone becoming acquainted with the particular type of opening in the screw 30 and thus prevent any tampering with the guard or loosening of the floating lock 28.

In the modification shown in Fig. 6, the lower member 8 is dispensed with entirely and instead the cotter key or pin 36 is used. This structure has been found desirable where there is not sufficient room to place a complete guard around the guy wire as sometimes the wall of a building or an adjacent guard will interfere with or prevent the use of a second complete guard.

It will be noted from our construction that the blocks 11 and 19 are each provided with a guy wire receiving recess and furthermore, that said blocks are interlocking, that is, they interlock with each other in such a manner that lateral movement of the blocks relative to each other is prevented when the screw 30 is tightened.

It is also our intention when found desirable to eliminate the ears 14 and 32 and spot weld the blocks 11 and 19 in place instead of riveting.

Having fully described our invention, what we claim as:

1. A guy wire guard comprising a pair of members, blocks with a central guy wire receiving recess therebetween, and means for interlocking said blocks whereby lateral movement of said blocks is prevented.

2. A guy wire guard comprising a pair of members, blocks having a central guy wire receiving recess carried by each of said members, means for interlocking said blocks whereby lateral movement of the same is prevented, and means carried by one of said members and the blocks carried thereby for clamping the guard on a guy wire.

3. A guy wire guard comprising a pair of members substantially U-shaped in cross section, blocks having a central guy wire receiving recess carried by each of said members, and means for interlocking the blocks of one member with the blocks of the other member for preventing lateral movement of said blocks.

4. A guy wire guard comprising a pair of members substantially U-shaped in cross section, longitudinally spaced apart blocks having a cen-

tral guy wire receiving recess carried by each of said members, means for interlocking said blocks for preventing lateral movement thereof, and means carried by one of said members and the blocks located therein for clamping the guard on a guy wire.

5. A guy wire guard comprising a pair of members, longitudinally spaced blocks having a central guy wire receiving recess therebetween, means for interlocking said blocks so as to prevent lateral movement thereof, a floating lock carried by the blocks of one of said members, and means for forcing said floating lock into frictional engagement with a guy wire.

6. A guy wire guard comprising a member substantially U-shaped in cross-section, a block therein provided with a guy wire-receiving recess, means carried by said block and movable between the latter and said wire for frictional engagement with said guy wire, and means operable through said U-shaped member for forcing said last mentioned means into said frictional engagement with said wire to lock the latter in place.

7. A guy wire guard comprising a member substantially U-shaped in cross-section, a block therein provided with a wire-receiving recess, means cooperating with said block for supporting said guard when the wire is in said recess, and means movably carried by said block and forcible outwardly therefrom into frictional engagement with said wire to lock the wire in place against said first mentioned means.

8. A guy wire guard comprising a member substantially U-shaped in cross-section, a block therein provided with a wire-receiving recess, movable means carried by said block for engagement with said wire, deformable means cooperating with said block for engaging said wire when the latter is in said recess, and means for forcing said first mentioned means against said wire toward said deformable means to clamp the wire in place.

9. A guy wire guard comprising a pair of members, blocks having guy wire positioning means therebetween, and means for interlocking said blocks whereby lateral movement of the same is prevented.

10. A guy wire guard comprising a pair of members, blocks between and separating said members, said blocks having a recess therebetween to receive and centralize said guy wire, means for interlocking said blocks against lateral movement, and means for clamping said blocks to the guy wire.

11. A guy wire guard comprising a pair of members substantially U-shaped in cross-section, blocks secured in said members and having a guy wire recess therebetween, and means for interlocking said blocks to prevent lateral movement therebetween.

12. A guy wire guard comprising a pair of members, longitudinally spaced blocks attached to said members, a central guy wire receiving recess formed between said blocks, means for interlocking said blocks so as to prevent lateral movement, and means for locking said blocks against longitudinal movement.

13. A guy wire guard comprising a pair of members substantially U-shaped in cross-section, a plurality of blocks carried by said members in longitudinally spaced position, said blocks provided with means therebetween for retaining said guy wire in position within said members, and means for clamping said members

together for preventing removal of one from the other.

14. A guy wire guard comprising a member substantially arcuate in cross-section, a block 5 therein with a guy-wire-receiving groove, clamping means between said block and wire for engagement with the latter, means opposed to said clamping means for co-operative engagement with said wire, and means for actuating said 10 clamping means toward said last-mentioned means for locking the guard in position against removal from said wire.

15. A guy wire guard comprising a member

of substantially trough-shaped cross-section, a block therein with a groove for receiving said wire, clamping means movable in said groove for frictional engagement with said wire, means opposed to and spaced from said clamping means and co-operable therewith to receive the wire therebetween, and means for actuating said clamping means against said wire to clamp the latter in place and lock the guard against removal from the wire.
